REFRIGERANT MIXTURE

Glenn F. Zellhoefer, Bloomington, Ill.

No Drawing. Application March 20, 1933,
Serial No. 661,789

1 Claim. (Cl. 252—5)

The present invention relates generally to refrigerant materials for automatic refrigerators, and particularly to the type of refrigerant material for the so-called "two-fluid machines", wherein there is a solvent material adapted to remain liquid throughout the operation of the refrigerator, and a refrigerant material adapted to have a liquid and a vapor phase in the cycles of operation, and adapted to be dissolved in the solvent.

Numerous refrigerants and numerous solvents are known and numerous combinations of these are known.

The present invention is directed to a new solvent material and to the combination thereof with well-known refrigerant material.

One object of the invention is the use of dichlor benzol as a solvent for a refrigerant.

Another object of the invention is the use of dichlor benzol and methyl chloride in combination.

An example of an apparatus in which the new materials have been successfully employed is described in my copending application Serial No. 25 651,306 filed January 12, 1933.

Briefly described, the apparatus specifically referred to comprises a still in which a mixture of solvent and refrigerant is heated to vaporize the refrigerant from the solution, a condenser wherein the vapor is condensed to a liquid state, an evaporator wherein the liquid is vaporized at reduced pressure, such evaporator being the effective cooling means, such as coils, in the apparatus, and an absorber in which vapors containing added heat units are again dissolved in the solvent. Suitable heat exchanging and circulation means are included, and automatic controls may be provided.

The particular characteristics of such machines are that the still operates at temperatures well above normal temperatures against which the refrigeration acts, such for example, at 210° F. to 250° F.; and that the cooling unit operates at temperatures much lower than normal, such as from 5° F. to 40° F. Various parts of the apparatus differ in the prevailing pressures as well as temperatures and both pressure and temperature determine the physical state of the free refrigerant, whether gaseous or liquid and determine the solubility relations between the refrigerant and the solvent. It is therefore very important that the solvent and the refrigerant be physically adapted for use as individual materials in certain places and for certain functions, and that they be mutually adapted for certain functions

when they are in combination. Other qualities not essential to refrigeration, but pertinent to practical usage control or limit the choice of solvent or refrigerant, such as odor, viscosity, heat capacity, boiling point, freezing point, volatility, chemical stability, reactivity, corrosive action, inflammability, toxicity, etc.

In the following description the particular advantages and merits of methyl chloride and of dichlor benzol and of their combination will become apparent as they are discussed with relation to these various important commercial factors.

Dichlor benzol

Throughout this description the material may be referred to as dichlor benzol, although there are three distinct chemical forms of it known as the ortho, meta and para forms. They are generally similar but differ in some respects. The invention may employ either form or any combination thereof. All forms boil at approximately 347° F. at atmospheric pressure which is far above the operating temperatures ordinarily contemplated. Hence the volatility at the operating temperatures is much less than with solvents having a lower boiling point. This is important in limiting the amount of solvent which vaporizes with the refrigerant and accompanies it in its journey through the rectifier means.

The ortho and meta types are liquid at all temperatures normally encountered in apparatus, and whatever small amount gets into the cooling means remains liquid and does not clog the apparatus. However, the para type freezes at about 127° F. This material might easily freeze solid in the cooling means or in some other part of the apparatus where temperatures lower than about 127° F. are encountered. The presence of refrigerant material with the wandering quantity of solvent may entirely prevent such solidification, or may lower the effective freezing point where solidification may occur. Hence there is a remote but not eliminated possibility of clogging where the para type is predominating. Commercial grades of dichlor benzol contain varying quantities of the three types, but the predominance of the ortho and meta types overcomes the tendency of the para portion to freeze out. The preferred form is the ortho type free from para type, although the commercial mixtures are entirely satisfactory for ordinary conditions of operation.

For practical and mechanical considerations it is advantageous that the dichlor benzols are not

corrosive towards iron, brass, copper, and bronze, and are inert of themselves, and to such metals, in the presence of air and water. Consequently, cast iron parts and flexible copper tubing may be employed in apparatus designed for use with them.

Methyl chloride

This material is a gas or vapor at ordinary 10 temperatures, and is subject to liquefaction by increased pressure and by lowered temperature. It is highly soluble in the dichlor benzol. Its refrigerant qualities apart from the dichlor benzol are well known. It is essentially odorless, and 15 only slightly toxic. It is non-corrosive towards iron, brass, copper and bronze, and non-reactive with dichlor benzol. It is difficultly inflammable.

Combination of dichlor benzol and methyl chloride

The dichlor benzols have a high solvent capacity for methyl chloride.

Apparatus of the two-fluid type may have a 25 rectifier unit which treats the vapors from the still to remove solvent therefrom and return it to the still. The high volatility of the new solvent, and the great difference in volatility between the solvent and refrigerant of this specific combination lessens the amount of solvent in the vapors, and hence the amount of heat exchange in the 30 rectifier. This contributes to high thermal efficiency.

In common use of the combination, the pressure on the high side may be from 35 75 to 100 pounds per square inch and on the low side from 6 to 28 pounds per square inch. These figures are merely exemplary of the range of pressure change and are not by any means to be considered 40 as limits. The properties of the refrigerant, as related to the solvent, permit circulation through

the cooling unit of a large amount of refrigerant per unit weight of solvent.

It is well known that there are other common refrigerants generally similar to and useful like methyl chloride, and that they can be used like 5 methyl chloride in a variety of solvents. Because dichlor benzol has very specific advantages and properties in combination with methyl chloride, it will offer the same order of advantage with other refrigerants which have the same 10 order of difference in properties or with mixtures of suitable refrigerant material. The specific solubility relations for refrigerant material, other than methyl chloride, may vary somewhat with corresponding changes in thermal efficiency. 15 Accordingly the present invention contemplates dichlor benzol as a new solvent, and the specific combination of methyl chloride and dichlor benzol. The proportions in which the solvent and refrigerant are used will, of course, depend 20 entirely upon the type of apparatus employed, and also upon the particular design.

While I prefer ortho or meta dichlor benzol, it is to be understood that whatever form or forms the dichlor benzol has, the refrigerant mixture 25 consists only of such material as the solvent, and a suitable refrigerant material, preferably a single substance such as methyl chloride. It is further to be understood that if the materials are adulterated by the substitution of other solvent 30 or refrigerant material in such a manner as to retain the substantial benefits and advantages of the unadulterated combination, then the adulterated composition is intended to fall within the scope of the appended claims. 35

What I claim is:

A refrigerant mixture for the absorption type of refrigeration apparatus consisting of normally liquid dichlor benzol as a solvent, and methyl chloride as a refrigerant. 40
